(57) **CLAIM**

The ornamental design for a mail and key holder, as shown and described.

DESCRIPTION

FIG. 1 is a perspective view of a mail and key holder showing our new design.

FIG. 2 is a front elevation view thereof.

FIG. 3 is a rear elevation view thereof.

FIG. 4 is a right side elevation view thereof, a left side elevation view being a mirror image of the right side elevation view.

FIG. 5 is a top plan view thereof.

FIG. 6 is a bottom plan view thereof; and,

FIG. 7 is a perspective view of the mail and key holder of FIGS. 1-6, but with a different panel insert.

The stippling on the panel insert of FIGS. 1-6 represents shading of a surface having contrast to the surface of the wire frame.

The broken line showing of mail and key holder is included for the purpose of illustrating portions of the "article" and forms no part of the claimed design.
